(57) **CLAIM**

The ornamental design for a paper feeder panel for a multi-function electrophotographic printer scanner, as shown and described.

DESCRIPTION

FIG. 1 is a top, front and right side perspective view of a paper feeder panel for a multi-function electrophotographic printer scanner showing our new design;

FIG. 2 is a top, front and right side perspective view of the paper feeder panel for a multi-function electrophotographic printer scanner in isolation;

FIG. 3 is a bottom, front, and left side perspective thereof;

FIG. 4 is a top, rear and left side perspective thereof;

FIG. 5 is a front elevation thereof;

FIG. 6 is a rear elevation thereof;

FIG. 7 is a right side view elevation thereof;

FIG. 8 is a left side view elevation thereof;

FIG. 9 is a top plan view thereof; and,

FIG. 10 is a bottom plan view thereof.

The features shown in broken lines depict environmental subject matter only and form no part of the claimed design.

1 Claim, 6 Drawing Sheets
